SCOOTER

Elbert E. Schaad, Berkeley, Calif.

Application April 24, 1934, Serial No. 722,113

10 Claims. (Cl. 208—182)

The present invention relates to improvements in a scooter or a child's vehicle consisting of a foot board supported by front and rear wheels and provided in the front thereof with a box-like

5 structure having handles projecting laterally therefrom, so that it may be propelled by the child placing one foot on the foot board, while holding the handles and kicking off with the other foot.

10 The conventional scooter is well known and the principal object of the present invention is to provide a means for facilitating the construction of a scooter by the child.

As a rule scooters are home-made products and 15 the only difficulty encountered by the child in making his scooter is involved in the hardware of wheel mounting. The foot board and the box-like structure supported on the front end thereof are made of wood and are constructed by the 20 child without difficulty. At the present time a child constructing a scooter as a rule takes some wheels from an old pair of roller skates and applies the same, by means of such tools as are available, in a rather unsatisfactory manner. Furthermore, old roller skates are not always available, and at times the child has to go to the expense of buying a new pair of roller skates for the sole purpose of breaking the same apart and utilizing the wheels for the scooter.

30 In the present invention it is proposed to facilitate the construction of a home-made scooter by commercially providing the necessary hardware which may be sold in a kit and at a reasonable price.

35 More particularly it is proposed in the present invention to provide a pair of wheel mountings for a scooter, which are constructed in such a manner that they may be easily applied to the foot board without the use of any tools.

40 Further objects and advantages of my invention will appear as the specification proceeds.

The preferred form of my invention is illustrated in the accompanying drawing, in which

45 Figure 1 shows a scooter made in accordance with my invention in side elevation;

Figure 2 the same scooter in top plan view;

Figure 3 an enlarged fragmentary detail view in plan of a portion of the foot board having my wheel mounting attached thereto;

50 Figure 4 a transverse section taken along line 4—4 of Figure 3; and

Figure 5 a fragmentary longitudinal section taken along line 5—5 of Figure 4.

55 While I have shown only the preferred form of my invention, I wish to have it understood that

various changes or modifications may be made within the scope of the claims hereto attached without departing from the spirit of the invention.

In its preferred form my scooter comprises a 5 board 1 preferably of wood, and of suitable width to allow a boy's foot to rest thereon, and of suitable length. On the front end of the board there is mounted a box 2 having a handle 3 projecting therefrom on both sides as at 4. The board is 10 supported by front and rear wheels 5 and 6 respectively, the front wheels being arranged immediately behind the box 2 and the rear wheels near the rear end of the board.

15 My invention is particularly concerned with these wheels and their mounting means which are shown in detail in Figures 3 to 5. While I have shown in the drawing a pair of wheels in each instance, it is apparent that a single wheel might be substituted for the pair of wheels without departing from the spirit of the invention.

Referring to the front wheel structure, two wheels 5 are inter-connected by a shaft 7, which latter supports a U-shaped element 8 having legs 9 and a cross-piece 10 projecting slightly above 25 the wheels. A rectangular plate 11 preferably of a length corresponding to the width of the foot board 1 has a round downward projection 12 presenting a flat lower face adapted to lie on the cross piece 10. The cross piece is secured to the 30 projection by means of a central screw 13, which allows the cross piece to be turned relative to the projection 12, and the cross piece may be locked in either one of two positions by means of a short lever 14 pivoted in lips 16 projecting from 35 the cross piece, and adapted to engage with one end in one of two recesses 17 provided in the bottom face of the projection 12, a spring 18 urging the lever into the recess. The two recesses are arranged in such a manner that when the 40 lever 14 is locked in one of the recesses 17 the cross piece 10 is positioned parallel to the plate 11, and when the lever is locked in the other recess 17 the cross piece is arranged at right angles to the plate 11. For normal use as shown 45 in Figures 1 and 2, the cross piece will be locked so as to run parallel to the plate 11 as shown in the different views.

The plate 11 is adapted for placing against the bottom face of the board 1 and has a plurality 50 of prongs 19 projecting therefrom which may be made to penetrate into the wood of the foot board in the manner shown in Figure 4 to hold the plate 11 against shifting movement. For further holding the plate to the foot board I pro- 55

vide the strap 20 which is preferably made in two sections 21 and 22. This strap is intended to pass around the foot board for holding the plate 11 thereto. The lower ends 5 of the two sections are passed around the lower edges of the plate 11 and then through slots 23 to lie against the upper edge of an intermediate section of the plate 11. These ends are also formed with a plurality of perforations 10 corresponding in their spacing and their arrangement to the prongs 19 so that the strap sections may be placed over the prongs and be held in position by the latter passing through the perforations. There are sufficient perforations to allow 15 the strap sections to be adjusted relative to the prongs, and the strap sections are preferably made to overlap as shown at 24, the degree of overlapping determining the operative length of the whole strap.

20 After the lower ends of the two strap sections are thus secured relative to the prongs the remaining portions of the two sections are guided around the sides of the foot-board and the upper ends are secured together by means of a suitable 25 buckle shown at 25. While any suitable buckle may be used for this purpose, I show a buckle involving a ring 26 pivotally secured to one of the strap sections as at 27, and having a lever 28 pivoted to its front member 29. The lever is 30 made in the form of a plate 30 having two side flanges 31 arranged in spaced relation, and the pivot 29 is spaced from the plate 30 as shown in Figure 4. A second pin 32 is also supported in the flanges near one end of the lever and is 35 adapted for pivotal engagement in recesses 33 formed in two flanges 34 rising in spaced relation from the other strap section.

Figure 4 shows the buckle in active position. For loosening the same the free end 35 of the 40 lever is thrown upward whereby it is swung on the pin 32 and the pivot 29 is also made to swing about the pin 32. This loosens the arrangement and the pin 32 may be lifted out of the recess in the lips 34. For fastening the 45 buckle the pin 32 is first engaged in the recess of the lips 34, whereupon the loose end 35 of the lever is swung about the pin 32 into the position shown in Figure 4, the buckle being locked in position by the pivot 29, the ring 26 being 50 thrown across the center of the pivot 32.

The manner of assembling the scooter by means of the wheel mountings thus provided will be readily understood from the foregoing description. The wheel mounting and the strap are 55 bought in the hardware store and after the child has assembled the wooden parts of his scooter, he secures the wheels in the manner previously described. He first approximates the length of strap necessary for his particular foot board, adjusts the length by placing the lower sections 60 of his strap over the prongs, then places the plate 11 against the under face of the board, drives the prongs into the wood and guides the loose ends of the strap around the foot board to 65 secure them by means of the buckle.

At times a child may desire to build a larger vehicle known as a coaster by arranging two of the foot boards in parallel relation and securing the same together by means of a suitable vehicle 70 body running at right angles thereto. In order to make my wheel mounting available for a coaster of that kind, the wheels have to be arranged at right angles to the foot board, and that is the reason why I provide for arranging 75 the wheels in two different positions, either

parallel to the foot board, or at right angles to the same, by means of the lever 14 engaging in the recesses 17.

I claim:

1. A scooter comprising a foot board, a wheel supported plate and a strap anchored to the plate for removably securing the plate to the bottom face of the board the strap having means underneath the board for adjusting the length thereof. 5

2. A scooter comprising a foot board, a wheel supported plate lying in supporting relation to the under face of the board, teeth rising from the plate projecting into the board, and a strap interlocked with the teeth for securing the plate to the board. 10

3. A scooter comprising a foot board, a wheel supported plate lying in supporting relation to the under face of the board, teeth rising from the plate and projecting into the board, a strap for securing the plate to the board, the strap being 20 made in two sections meeting below the board and being perforated for anchoring engagement with the teeth in different positions, whereby the full operative length of the strap may be adjusted, and means for connecting the two sections above the 25 board.

4. As an article of manufacture, a wheel mounting having a strap for removably securing the same to a board or the like the strap being anchored to the mounting for freedom of adjust- 30 ability of the length of the strap at the anchoring.

5. As an article of manufacture, a wheel mounting comprising a pair of wheels, a plate mounted thereover so as to be supported by the wheels, a strap for securing the plate to the bottom face of a board or the like, and pins rising from the plate and extending into the board material for eliminating movement of the plate relative to the board, the strap being anchored in said pins. 40

6. A scooter comprising a foot board, a wheel supported plate lying in supporting relation to the under face of the board, teeth rising from the plate and projecting into the board and a strap for securing the plate to the board, the strap 45 having two ends meeting below the board and being perforated for anchoring engagement with the teeth in different positions, whereby the full operative length of the strap may be adjusted.

7. As an article of manufacture, a detachable 50 wheel mounting for a scooter having a strap for removably securing the same to a board or the like, the strap being anchored to the mounting.

8. A scooter comprising a foot board, a wheel mounting and a strap anchored to the mounting 55 and operable manually and without the aid of tools for securing the mounting to the foot board.

9. As an article of manufacture, a wheel mounting comprising a pair of wheels, a plate mounted thereover so as to be supported by the wheels, 60 a strap anchored to the plate for securing the plate to the bottom face of a board or the like, means for joining the ends of the strap and means intermediate the ends of the strap for adjusting the length thereof. 65

10. As an article of manufacture, a wheel mounting comprising a pair of wheels, a plate mounted thereover so as to be supported by the wheels, a strap for removably securing the plate 70 to a board or the like, means for anchoring the strap to the plate, and means associated with the anchoring means for adjusting the overall length of the strap. 75
